UNITED STATES PATENT OFFICE.

FRANK EARL HOLLAND, OF NORTH TONAWANDA, NEW YORK.

SPRING CONSTRUCTION.

No. 911,499.

Specification of Letters Patent.

Patented Feb. 2, 1909.

Application filed December 24, 1907. Serial No. 407,978.

To all whom it may concern:

Be it known that I, FRANK EARL HOLLAND, a citizen of the United States, residing at North Tonawanda, in the county of Niagara and State of New York, have invented certain new and useful Improvements in Spring Constructions, of which the following is a specification.

This invention relates to spring cushion constructions and more particularly to devices of this character employed in the backs of the seats of automobiles and similar structures, and has for its object to produce a simply constructed and easily applied device whereby the labor of upholstering devices of this character is materially reduced, and the initial cost of the construction also materially reduced.

In attaching cushions to the backs of seats of automobiles and similar vehicles, great difficulty has been experienced in applying the upholstering, and providing a cushion structure possessing sufficient resistance to prevent the same from becoming displaced and presenting an uneven appearance after a short period of use, or when subjected to severe strains or shocks incident to the operation of the vehicle.

The principal object of the present invention is to produce a device of this character possessing abnormal resisting power, so that it will withstand the shocks and strains to which it may be subjected without getting out of shape, but retain a symmetrical appearance at all times, and quickly recovering its shape after the pressure is removed.

Another object of the invention is to produce a device of this character in which the resistance is placed at points where the greatest pressure occurs, without increasing the expense or weight of the device.

In the drawing illustrative of the invention is shown the preferred embodiment thereof, and in the drawing thus employed:—Figure 1 is an elevation of the improved device detached. Fig. 2 is a section with a portion of the vehicle body attached and also in section. Fig. 3 represents enlarged perspective details showing the manner of coupling the auxiliary springs and stay wire.

In the improved device a frame is employed for supporting the springs of peculiar and novel construction, and consisting of two longitudinal bars or bands 10—11 preferably of band steel, and a plurality of

relatively long substantially vertical bars 13, the central bar being perpendicular and the remaining bars gradually increasing in angularity toward the outer or side bars, the outer bars conforming to the upwardly and outwardly diverging sides of the seat back, the upper ends of these bars 13 terminating near the top of the seat back indicated at 14, and their lower ends extending to the bottom of the seat back, as shown in Fig. 2. The bars 13 are riveted or otherwise secured to the horizontal bars 10—11 where they cross the same, as indicated at 15, the ends of the bars 10—11 being likewise adapted to be secured to the seat back 14 by rivets or other suitable fastening means.

Intermediate the bars 13 are shorter bars 16, inclined to correspond to the bars 13 and riveted as at 17 to the bars 10—11, the upper ends of the shorter bars 16 extending above the upper horizontal bar 10 and in line with the bars 13.

Two sizes of springs are employed in the improved construction, a larger and longer set of springs 18—19 being connected respectively to the bars 10—11 where the bars 13 cross them, the springs being preferably secured by the same rivets 15 which couple the bars 13 to the bars 10—11, while smaller and shorter springs 20—21 are connected to the bars 16, the springs 20 being connected to the shorter bars above the bars 10 preferably by tongues 22 cleft from the bars 16, while the springs 21 are secured to the bars 16 intermediate the bars 10—11 and likewise opposite the spaces between the springs 18—19, preferably by clips 23 cleft from the bars 16. The springs 20 will be spaced uniformly above the springs 18, so that the intervals between the springs are substantially uniform, and the springs also uniformly distributed over the whole surface of the framework composed of the bars 10—11—13—16; as shown in Fig. 1. The larger and longer springs 18—19 thus project beyond the shorter and smaller springs 20—21, as illustrated in Fig. 2. The springs are thus arranged in horizontal rows, but "break joints" vertically, as shown.

The springs are all of the conical form with the longer springs arranged with their smaller ends next the bars 13, and the shorter springs arranged with their larger ends next the bars 16. Each of the outer whirls or convolutions of the shorter springs has a straight terminal indicated at 25, and bear-

ing upon these terminal portions is a rectangular wire stay member 26, the stay member being coupled to the respective portions 25 by clips 27, one of which is shown enlarged in Fig. 3. The stay member 26 is thus an important feature of the construction, and materially strengthens the device against lateral movement, while at the same time not materially increasing the weight or the expense of manufacture.

10 As shown in Fig. 2, all of the springs are disposed near the upper portion of the back 14, so that the upper portion of the upholstering, indicated by the dotted line 24, is firmly supported at the point where the greatest pressure occurs, so that the greatest 15 resistance is provided where most required. By reference to Fig. 2 it will be noted that the upper row of springs 20 are arranged near the upper end of the upholstering, while the second row of springs 18 are spaced a short distance from the upper row, and the remaining rows of springs disposed a short distance below these, the shorter and 20 smaller springs alternating with the longer and larger springs, as shown, so that when pressure is applied, the larger and longer springs receive the first impact and the shorter and smaller springs become active 25 only when the larger and longer springs have been deflected for a considerable portion of their lengths. The larger springs thus serve to hold the upholstering portion of the cushion in position under ordinary 30 conditions of ordinary pressure, but in the event of abnormal pressure being applied to the upholstering, as when the vehicle meets obstructions in the roads, the shorter springs then become active and materially increase 35 the resistance and effectually prevent undue collapsing. The contour of the cushion is thus maintained, and restored when the pressure is withdrawn. The bands or bars may be of any required size or strength and arranged 40 at any distance apart, and the springs may be correspondingly sized to adapt the device to any of the various makes of automobiles and similar vehicles.

45 By the employment of this simple device, great saving of time and labor occurs, as no necessity exists for tying the individual springs in position, as in the construction of ordinary forms of spring cushions.

The invention is simple in construction 50 and can be cheaply manufactured. In constructing a cushion according to the improved means the frame, with the springs in position thereon, is placed against the back 14 of the automobile and riveted fast there- 55 to, and the upholstering material applied over the springs in the usual manner. All the springs of the cushion structure are thus applied simultaneously, which very materially reduces the time and labor required to construct a cushion, and dispenses with

the necessity for tying each individual spring in position, as in cushions heretofore constructed.

Having thus described the nature of the invention, what is claimed as new is:—

70 1. A spring construction comprising a frame including horizontal bars and a series of spaced bars crossing the horizontal bars and at uniformly increasing angles from the center toward the ends thereof, a set of springs connected to the bars at their points of intersection, another set of springs connected to the bars off from their points of intersection and a substantially rectangular stay connected to the last mentioned springs 75 to couple the latter together.

80 2. A spring construction comprising a frame including horizontal bars and a series of spaced bars crossing the horizontal bars and at uniformly increasing angles from the center toward the ends thereof, a set of 85 springs connected to the bars at their points of intersection, another set of springs connected to alternate angularly arranged bars and out of alignment with the aforesaid set 90 of springs, one set of springs being longer than the other set of springs.

95 3. A spring construction for the backs of automobiles comprising a series of spaced horizontal bars and a series of spaced bars crossing the horizontal bars at uniformly increasing angles from the center toward the ends thereof, with each alternately angularly arranged bar extending at the ends beyond the remaining angular bars, and 100 adapted to be connected to the seat back at the extended ends, relatively large springs connected to the longer bars at their junction with the horizontal bars and relatively small springs connected to the shorter angular bars.

105 4. A spring construction comprising a frame formed of horizontal and a series of spaced bars crossing the horizontal bars, the two sets of bars being connected together at their points of intersection, alternately arranged horizontal rows of relatively large and long and relatively small and short single cone 110 springs secured to the frame, the apexes of the larger springs being directed toward the frame and the apexes of the shorter springs being directed toward the base of the larger springs, and a stay connected to the apexes 115 of the shorter springs to couple the latter together.

120 5. A spring construction comprising a frame formed of horizontal and spaced bars connected at their points of intersection, the alternately arranged spaced bars being longer than the remaining spaced 125 bars, the shorter spaced bars each having a pair of tongues arranged upon opposite sides of the horizontal bars, a set of springs connected to the bars at their points of intersection, and another set of springs con- 130

nected to the shorter spaced bars by the tongues of the latter, one set of springs being shorter than the other set of springs.

6. A spring comprising a frame formed 5 of horizontal bars and a series of spaced bars crossing the horizontal bars at uniformly increasing angles, the two sets of bars being connected at their points of intersection, the alternately angularly ar- 10 ranged bars being longer than the remaining angularly arranged bars, the shorter angularly arranged bars, each having a pair of tongues arranged upon opposite sides of the horizontal bars, one set of springs con- 15 nected to the bars at their points of intersection by the same means which connects the intersecting bars together, another set of springs connected to the shorter angularly arranged bars by the tongues of the latter, 20 one set of springs being shorter than the

other set of springs, and a substantially rectangular shaped stay member connecting the shorter set of springs:

7. A spring construction comprising horizontal bars and bars crossing the horizontal 25 bars and connected thereto, the alternately arranged second mentioned bars having tongues, one set of springs connected to the bars at their points of intersection by the same means which connects the intersecting 30 bars together, and another set of springs connected to said alternate bars by means of said tongues.

In testimony whereof I affix my signature, in presence of two witnesses.

FRANK EARL HOLLAND.
